UNITED STATES PATENT OFFICE.

CLAES WELIAM BOMAN, OF NEW YORK, N. Y., ASSIGNOR TO EAGLE PENCIL COMPANY,
OF NEW YORK, N. Y.

DESIGN FOR A PROPELLING-PENCIL.

No. 39,906.

Specification for Design.

Patented April 6, 1909.

Application filed January 13, 1909. Serial No. 472,145. Term of Patent 7 years.

To all whom it may concern:

Be it known that I, CLAES W. BOMAN, a citizen of the United States, residing at New York, county and State of New York, have invented a new, original, and ornamental Design for Propelling-Pencils, of which the following is a specification, reference being had to the accompanying drawing, forming part thereof.

The figure is a perspective view of the propelling pencil, representing it in its actual size.

The pencil is noticeably thick and long. The case of the pencil is cylindrical with the exception of the tip, which is conical; and it is smooth throughout its length, with the

following exceptions viz: There is an annular bead *a* some little distance back of where the conical tip merges into the cylindrical body of the case; and the cylindrical body of the case terminates in a circumferentially "milled" head *b*—the milled appearance thereof being produced by transversely nicked annular corrugations as shown.

I claim—

The ornamental design for a propelling pencil as shown and described.

CLAES WELIAM BOMAN.
